UNITED STATES PATENT OFFICE.

JAMES SMITH AND MAXFIELD E. CONSTABLE, OF DEPOSIT, NEW YORK.

SHINGLE ROOF.

Application filed June 12, 1923. Serial No. 644,930.

To all whom it may concern:

Be it known that we, JAMES SMITH and MAXFIELD E. CONSTABLE, citizens of the United States, residing at Deposit, in the county of Broome and State of New York, have invented certain new and useful Improvements in Shingle Roofs, of which the following is a specification.

Our invention relates to roofs of buildings and it has for its object to provide a form of shingle roof, put on in sectional form, simple in construction, superior in wearing quality and fire resistance and rigidity, at the same time having an artistic appearance and design in imitation of a tile roof.

With these objects in view, our invention consists in certain novel features of construction and arrangement of parts as will be hereinafter more fully described and pointed out in the claims; reference being had to the accompanying drawings, in which:

Fig. 1 is a fragmentary plan view of a roof section,

Fig. 2 is a front edge view of a roof section,

Fig. 3 is a cross section of a roof section,

Fig. 4 is a perspective view of a fragmentary part of roof, formed with a modified form of roof section, and

Fig. 5 is a perspective view of a fragmentary part of roof, formed of our roofing section.

The same reference characters denote like parts in each of the several figures of the drawings.

In carrying out our invention, we have the roof, formed of sectional strips, laid flat, as shown in Fig. 4, or a roof covered with sectional strips, having in each, a series of transverse ridges 2.2, separated by valleys 3.3, as shown in Figs. 1 and 5. In carrying out our invention, whether flat as shown in Fig. 4 or ridged as shown in Fig. 5, we provide sectional strips formed as follows: a sectional strip A, having an outer surface of a layer of slate surfaced roofing b or other weather wearing and adaptable flexible material; on the under side of the front half portion of this section as shown in Fig. 3 and about one-half in width of the entire section b, we provide a layer of adhesive material c, composed of asphaltic or other appropriate material of that kind, and on this surface we mount a strip or section of that width, of thin metal d, such as tin

or other light bending material, as a reinforcing and stiffening material and on the under side of this we apply a coating of paint; the outer slate surfaced material b being for the weather or wearing surface and the adhesive material c being for the purpose of securely adhering the reinforcing section d to the weather wearing section and the three layers b, c and d being firmly united together by pressure and on the under side of the metal section d, we provide a coating of paint. In the lower edge of this section A, we provide a series of interstices 4.4 as shown in Figs. 4 and 5 of shallow depth and having the ends of each, at an oblique angle 5.5. In another form of our device, we have the section A thus formed of successive layers of material b, c, and d, as before described and we then insert the section in a mould or shaper under pressure and so mould and shape it, in ridges as shown in Figs. 1, 2 and 5, the metal strip d, as shown in Fig. 3, affording a stiff shaping supporting means producing the form shaped as shown in Figs. 1, 2, 3 and 5, having across the section, the series of curved transverse ridges 2.2 and extending on each side thereof, into the horizontal spaces 3.3, forming valleys between the ridges, each valley having a recess or interstice 4.4 at the lower edge thereof, between the ridges, with diagonal ends 5.5 therein, as shown in Figs. 1 and 5. These sections, whether flat, as shown in Fig. 4, or ridged, as shown in Figs. 1, 2, 3 and 5, are then applied to forming the roof as follows: We first lay along the lower edges of the roof, a flat strip of surface material A', made up of flat straight edge sections along its entire length, as shown in Figs. 4 and 5; upon this flat strip of sections is laid a series of flat sections, as for a flat roof, as shown in Fig. 4, or a series of ridged sections, as shown in Fig. 5. Whether laid flat or in ridges, the flat extensions of one section, join the flat extension of the next section and so on until an entire course of the strip shingles are laid, either flat as shown in Fig. 4 or with a series of alternate ridges or valleys, as shown in Figs. 1 and 5. These layers are alternate, so that their joints will meet over the solid surface of the sections beneath. Also in the edge of the valley sections are the interstices or recesses 4.4, having the ends 5.5 thereof at an angle, as before described and thus we have in this form of

roof, the combination of the transverse ridges in each section with the recessed edges as before described to form an artistic appearance and finish in the roof; also the 5 metal layers overlap each other as before described herein and are fastened in the same manner so that no matter what the wear of the exposed weather portion is, there is a resultant metal roof beneath. The open ends 10 of the ridges of the lower course may be closed by blocks of wood 6.6 inserted therein in any convenient manner.

Having thus described our invention, what we claim as new and for which we desire 15 Letters Patent, is as follows:

1. A roof comprising a series of overlapped substantially rectangular sheets, each sheet having its front edge portion projecting over the rear edge portion of an 20 adjacent sheet and the front edge portion of each sheet being provided with spaced notches having inner edges arranged paral-

lel to the front edge of the sheet, each sheet being formed of a lower layer of metal and an upper layer of slate surfaced roofing material, adhesive securing said layers together, the lower layer of each sheet being of the same length but of less width than the upper layer and the rear edge of the lower layer being spaced from the rear edge 30 of the upper layer.

2. A roofing as claimed in claim 1 in which the portions of the sheets between the notched portions are bent upwardly to form substantially semi-cylindrical convex ridges. 35

3. A roofing as claimed in claim 1 in which the metal layers of the sheet are overlapped to form a complete unbroken roofing of metal.

In testimony whereof we have affixed our 40 signatures.

JAMES SMITH.
MAXFIELD E. CONSTABLE.
